[57] CLAIM

The ornamental design for a crib, as shown and described.

DESCRIPTION

FIG. 1 is a perspective view of the crib;

FIG. 2 is a top plan view of the crib;

FIG. 3 is a side elevational view, the opposite side being
identical thereto;

FIG. 4 is a bottom plan view of the crib; and,

FIG. 5 is a right end of the crib, the left end being a mirror
image thereof.
